WALKING FIGURE TOY

Jacques Villemajane, Paris, France, assignor of one-half to Compagnie du Celluloid Petitcollin-Oyonnith, Paris, France, a corporation of France

Application April 19, 1948, Serial No. 21,959
In France May 5, 1947

6 Claims. (Cl. 46—105)

1

This invention relates to an animated toy, doll or automaton on two feet, of the type in which a double oscillating movement in opposite directions about a common axis by means of a motor operates the two feet through a plurality of links and a crankshaft having crank pins opposed by 180° for alternately moving each leg.

One object of the invention is to provide an animated toy both feet of which will constantly remain in contact with the surface supporting the toy during the alternate movement of the two feet.

Another object is to obtain a movement of the arms of the toy or doll connected with the movement of the feet, and also a rotation of the head and a movement of the lower jaw.

Another object is to obtain bending of the knees and also of the elbows.

A still further object is to obtain a turning movement of the feet on the supporting surface.

With these objects in view and others which will appear hereafter, the feet of the animated toy are provided with rollers which rest on the supporting surface and enable each foot, by the oscillating movement of a rod, to advance alternately while the other foot rests on said surface without sliding, thus securing a steady walk of the animated toy as both feet are always in contact with the surface that bears it.

In an embodiment of the invention which still better imitates human walk, a second rod for each leg connects the motor or the body of the animated figure with the foot by means of a pivot, one rod moving the foot forward while the second rod forces the other foot to remain in contact with the supporting surface.

In the accompanying drawings which illustrate diagrammatically, by way of example, various embodiments of the invention, the contours of the animated toy being outlined around the mechanism:

Figure 1 is a side view and Figure 2 a front view of the mechanism comprised of oscillating rods.

Figures 3 and 4 are side and front views, respectively, of an embodiment having two rods for each foot.

Figures 5 and 6 are side and front views, respectively, of a modified form for bending the knees.

Figure 7 shows a detail view of a modified form of the crank pins operating the rods.

Figure 8 shows a modified form of the sole of the foot for causing pivoting of the animated toy.

Figure 9 shows means for oscillating the arms of the toy.

Figure 10 shows a modified form of the latter means.

Figure 11 represents a modified form of the

2

connection of the arms with their oscillating means.

Figure 12 shows an embodiment of the oscillating means of the arms, adapted to bend the fore-arm,

Figure 13 shows means for turning the head of the animated toy,

Figure 14 shows means for moving the lower jaw of the head,

Figure 15 is a plan view from below of a foot provided for a turning movement controlled by the arm of the toy,

Figure 16 is a longitudinal view of the foot partly in section, the fore rollers being in the straight position,

Figure 17 is a plan view from below of a foot having a guided turning movement,

Figure 18 is an axial section of a device for regulating the speed of the motor,

Figure 19 is a general view of a toy operated as in Figure 15.

Referring to Figures 1 and 2, the rods 1 attached to each foot 2 pivot at their upper ends on a pin 3 fixed to the body of the toy representing an animated figure or to the motor 7 of any type, which is shown in Figure 2 as a spring-operated motor. The rod 1 is formed with an elongated slot 4 into which is engaged a crank pin 5 of a crankshaft 6, the other crank pin of which is opposed by 180° to the former crank pin and engages the corresponding elongated slot 4 of the rod 1 of the other leg. The crank shaft 6 is rotated by means of the motor 7 which will generally comprise a simple spiral spring. According to the invention, each foot 2 bears, by means of a spindle 9, one or more rollers 8 which may be hidden within the soles of the feet, generally under the heel.

When the motor turns, the crank pin 5 moves the rod 1 forward, the latter pivoting about the pin 3. The roller 8 rolls on the bearing surface (which may be, for instance, a table or the floor), the foot 2 moving forward, while the other foot rests on the bearing surface owing to the weight of the toy, without sliding, thus allowing the body of the toy to move forward. When the first foot 2 has ceased advancing, the other foot is moved forward by its rod 1 and the corresponding crank pin 5, said latter foot being supported by its roller 8, and walking of the toy is thus obtained.

The rods 1 may be formed by the legs themselves, but in general it is preferred to have a mechanism distinct from the body that surrounds it.

Lateral steadiness is perfect as the rods 1 are of the same length and both feet 2 are always in contact with the bearing surface. Proper longitudinal steadiness is due to the broad area formed by the two feet, enabling the toy to make big steps without any other fulcrum.

The rollers 8 and the soles may be coated with rubber or any other material so as to afford good adherence and compensate for unevenness of the bearing surface.

Turning to Figs. 3 and 4 illustrating a preferred embodiment of the invention, the body of the toy figure carries a power unit 7, say a clockwork that transmits its energy through a gearwork to a horizontal crank shaft 6 the crank pins of which control respectively the upper ends of two connecting links 10 arranged longitudinally of each leg of the toy figure. Said links 10 that are provided each with a longitudinal slot 12 are guided by a common elongated horizontal pivot 11 engaging the two slots 12. Said connecting links or rods are associated in each leg with a substantially parallel link or rod 1 pivoted through its upper ends to a pivot 3 rigid with the toy body while the lower ends of the rods 1, 10 of each leg are pivotally secured respectively at 13 and at 14 with a foot member 2.

It is thus apparent that the elongated pivot 11 forms a bearing member through which the body and driving unit are held in stable equilibrium conditions on the two leg links 10 that are always at an angle with one another; each driving link 10 when urged forwardly by the crankshaft constrains the corresponding foot 2 to slide or roll over the ground through the reduced contact surface provided by the roller 8 carried by the rear pivoting axis 14 thereon while the front of said foot is raised. The friction between said forwardly projected foot and the ground is much less than that exerted by the other foot 2 bearing throughout its length on the ground. When one foot 2 has thus advanced by one step, the forward movement of the whole toy constrains it to bear in its turn on the ground throughout its length and at this moment the driving link 10, that is then to the rear, raises the rear foot 2 which is gradually urged forwards. These combined movements stimulate a human gait without requiring any external bearing points.

If bending of the knees be desired, the two rods 1 and 10 (Figures 5 and 6) may be pivoted to the knee instead of being pivoted to the foot. The rod 10 is connected to the knee by the spindle 13, and the rod 1 pivots on a spindle 15 carried by the knee, the leg being integral with the foot. The roller 8 is supported at the forward portion of the foot by a spindle 9.

The rollers may be provided with a free or unidirectional wheel (not shown in Figures 5 and 6, but such as shown in Figure 16). The foot is thus better held on the bearing surface during forward walking and cannot slide backwards.

The crankshaft 6 (Figure 7) may be made movable sidewise of the body along its axis. In such case, the crank pins 5, instead of being at right angles, are inclined to the axis of the crankshaft. It follows that by displacement along the axis, the crank pins being moved from the position in full lines to the position in dotted lines, the rods 1 or 10 are raised by variable and unequal lengths of the crank pins, and the two feet are given different displacements which cause the toy to turn at will on a larger or shorter radius in either direction.

If it be desired to cause the animated toy to dance or pivot on its own body, a rotatable roller 16 (Figure 8) is provided at the center of the sole. Said roller is operated by the motor by

means of any gearing of variable length, constituted by a stem 17 having a Cardan joint or ball joint or by a Bowden cable. It is thus possible to cause the toy to turn and pivot on one foot or successively on either foot.

Movement of the arms 18 of the toy (Figures 9 and 10) may be obtained by attaching the arms to either of rods 1. It may be obtained by means of a second crankshaft 19 (Figure 10) connected with the arm 18 and supported on the motor 7. The crankshaft 19 engages a second slot 20 in the rod 10, so that the crank pin 21 reciprocates on the axis of the crankshaft 19.

In the case of Figure 11, the crankshaft 19 rotates a tube 22 guided within an outer tube 23. The inner tube 22 rotates the arm 18 of the toy, so that oscillation of the crankshaft 19 causes oscillation of the arm 18. Oscillation may be made resilient by connecting the crankshaft 19 with the arm 18 through a spring or a rubber strip 24, provided at its other end with a cup 25 carrying along by friction another cup 26, borne by the arm 18. Such resilient connection allows the position of the arm to be modified in respect of the body of the toy independently of the oscillation of the arm.

If it be desired to obtain a movement of the fore-arm irrespective of the movement of the whole arm, the above-described mechanism of the arm, instead of being connected to the arm 18 itself, may be connected to a rod 27 (Figure 12) integral with the arm. Another rod 28 oscillating about a pin 29 is pivoted by a pin 30 to a rod 31 which is pivoted to the rod 27 of the arm. During oscillation of the rod 27, the fore-arm will thus oscillate in respect of the arm 18.

Movement of the head may be obtained by means of a lever 32 (Figure 13) operated by one of the rods operating the legs. Said lever 32 pivots about the axis of a stem 33 integral with the head of the toy. The head may be guided by means of co-axial cylinders 34, 35 which form the neck of the doll. The head will thus turn to the right and the left.

Movement of the lower jaw (Figure 14) may be obtained, to imitate a person talking, by means of a stem 36 operated by a crankshaft 37, the crank pin 38 of which engages a slot in the rod 10 or the rod 1.

In the case of Figures 15, 16 and 19, the foot 2 of the toy bears two pairs of rollers 40, 41, each pair being mounted on a common spindle. The forward pair 41 is provided with a free or unidirectional wheel formed, for example, of an eccentric segment 42 (Figure 16) which allows the rollers 41 to turn freely when moving forward but prevent them from turning backward. This device thus enables the foot to advance rapidly without being liable to slide backwards.

The forward pair of rollers 41 is adapted to be given an angle variable with the direction in which the foot advances. To this purpose, their common spindle is integral with a lever 43 connected to any suitable gearing, shown, for example, as a Bowden cable 44. The latter may be, more particularly, connected to the operating mechanism of the arm 18 (Figure 19) such as described hereabove, so that the movement of the arm gives the pleasant result of causing the toy to turn. The change of angle of the rollers 41 may also be effected by telecontrol.

According to Figure 17, the rear rollers 40 have their spindle perpendicular to the longitudinal axis of the foot. The two forward rollers 41 are mounted on two separate spindles which converge

rearwardly, preferably towards a point 45 situated on the common axis of the rear rollers 43. The foot 2 of the toy leans against a rim 46 formed on the table or other surface on which the toy walks. The foot is preferably provided with a ball 47 for facilitating its sliding in respect of the rim 46.

The foot placed forward being raised at its fore part and leaning against the curved rim 46, imparts turning movement to the toy, while the 10 foot placed at the rear resting on the supporting surface advances on its fore rollers 41' and pivots about the point 45.

If it be desired to vary the speed of the toy, the speed of its motor may be modified by any suitable means. For example, the arm 18 or any part of its mechanism, such as the stem 27 (Figure 19), may be connected to a lever 48 resting on a plate 49 integral with the shaft 50 of the motor (such as 7 shown in Figures 1 and 2). By drawing 15 the end of the lever 48 away from the plate 49 to the position shown in dotted lines in Figure 18, the speed of the motor is increased since the friction on plate 49 is released, and consequently the 20 toy will walk faster. But as the masses 51 are thrown further away from their shaft, due to the increase of centrifugal force, and as they carry the plate 49 to the left, the plate is again brought into contact with the lever 48, which causes slackening of the motor, until a steady position is attained. If the motor should be given a lower 25 speed, or even stopped, the lever will be pressed more strongly against plate 49.

In all the devices described the motor may be an electric motor to which current may be supplied by contacts placed below the feet. The toy may also bear accumulators or primary cells, preferably in its feet so as to increase steadiness. A clockwork may also be employed. The toy may be operated by telecontrol effected by contacts or by radio-transmission. The different mechanisms may be varied or combined with other devices without departing from the scope of the invention.

What I claim is:

1. A walking doll which comprises, in combination, a body, two feet, the rear part of the sole of each of these feet being arranged to oppose less friction than the front part thereof to longitudinal running on the floor, two rods journaled to said feet about respective transverse axes located in the rear portions of said feet, said rods extending upwardly and being both pivoted to said body about a common transverse pivot axis, two rods pivoted to said feet about respective transverse axes located ahead of the above mentioned axes, said last mentioned rods extending upwardly, a transverse spindle carried by said body parallel to said pivot axis and located ahead thereof, the two last mentioned rods being provided with longitudinal guiding slots respectively, said transverse spindle slidably engaging said slots, a crank-shaft journaled in said body about a transverse axis located above said transverse spindle and having crank pins at 180° to each other, said crank pins being journaled in the upper parts of the two second mentioned rods respectively, and motor means carried by said body for rotating said crankshaft.

2. A walking doll which comprises, in combination, a body, two feet, the front part at the sole of each of these feet being frictionally slidable on the floor, at least one roller journaled in each

of said feet about a transverse axis forming the rear end of the sole of each of said feet, two rods journaled to said feet about the axes of said rollers respectively, said rods extending upwardly and being both pivoted to said body about a common transverse axis, two rods pivoted to said feet about respective transverse axes located ahead of the axes of said rollers, said last mentioned rods extending upwardly, a transverse spindle carried by said body parallel to said pivot axis and located ahead thereof, the two last mentioned rods being provided with longitudinal guiding slots respectively, said transverse spindle slidably engaging said slots, a crank-shaft journaled in said body about a transverse line located above said transverse spindle and having crank pins at 180° to each other, said crank pins being journaled in the upper parts of the two second mentioned rods respectively, and motor means carried by said body for rotating said crankshaft.

3. A walking doll according to claim 2 in which said crank pins are oblique with respect to said crankshaft and said crankshaft is slidable transversely with respect to said body for adjustment therein.

4. A walking doll according to claim 2 further including arms movable with respect to said body and operatively connected with the two second mentioned rods, respectively.

5. A walking roll according to claim 2 in which each foot includes two rollers journaled therein about the same transverse axis, to form the rear end of the sole of said foot, said two rollers being located respectively on either side of the longitudinal axis of said foot, each foot further including, in the front part thereof, two rollers journaled therein about respective axes oblique with respect to said longitudinal axis and converging toward the intersection of said longitudinal axis with the common axis of rotation of the two first mentioned rollers, said two front rollers forming the front end of the sole of the foot.

6. A walking doll according to claim 2 in which each foot includes two rollers journaled therein about the same transverse axis, to form the rear end of the sole of said foot, said two rollers being located respectively on either side of the longitudinal axis of said foot, each foot further including, in the front part thereof, two rollers journaled therein about respective axes oblique with respect to said longitudinal axis and converging toward the intersection of said longitudinal axis with the common axis of rotation of the two first mentioned rollers, said two front rollers forming the front end of the sole of the foot, and a ball journaled in said foot and projecting from the outer side of the front thereof.

JACQUES VILLEMEJANE.
